(57) **CLAIM**

The ornamental design for a battery powered power supply with built-in flashlight, as shown and described.

DESCRIPTION

FIG. 1 is a front perspective view of the battery powered power supply with built-in flashlight showing my new design;

FIG. 2 is a front elevational view thereof;

FIG. 3 is a rear elevational view thereof;

FIG. 4 is a right side elevational view thereof (the left side comprising a mirror view of the right side elevational view);

FIG. 5 is a top plan view thereof; and,

FIG. 6 is a bottom plan view thereof.

The lines which are applied broken are used as surface shading, and are not intended to show unclaimed subject matter.

1 Claim, 5 Drawing Sheets

FIG. 1**FIG. 2****FIG. 3****FIG. 4*****FIG. 5***

FIG. 6
